[57] CLAIM

The ornamental design for a middle shelf for use in a bussing cart, as shown and described.

DESCRIPTION

FIG. 1 is a top plan view of a middle shelf for use in a

bussing cart in accordance with a first embodiment of the present invention;

FIG. 2 is a bottom plan view of the middle shelf in accordance with the first embodiment of the present invention;

FIG. 3 is a front elevational view of the middle shelf in accordance with the first embodiment of the present invention, with the back elevational view being a mirror image thereof;

FIG. 4 is a right side elevational view of the middle shelf in accordance with the first embodiment of the present invention, with the left side elevational view being a mirror image thereof;

FIG. 5 is a top plan view of a middle shelf for use in a bussing cart in accordance with a second embodiment of the present invention;

FIG. 6 is a bottom plan view of a middle shelf in accordance with the second embodiment of the present invention;

FIG. 7 is a front elevational view of the middle shelf in accordance with the second embodiment of the present invention, with the back elevational view being a mirror image thereof;

FIG. 8 is a right side elevational view of the middle shelf in accordance with the second embodiment of the present invention, with the left side elevational view being a mirror image thereof; and,

FIG. 9 is a perspective view of the middle shelf of the first embodiment of the present invention in use in a bussing cart.
